UNITED STATES PATENT OFFICE.

JOHN W. STEPHENSON, OF TOLEDO, OHIO, ASSIGNOR TO THE NATIONAL MALLEABLE CASTINGS COMPANY, OF CLEVELAND, OHIO, A CORPORATION OF OHIO.

RAIL-JOINT.

1,252,368.

Specification of Letters Patent.

Patented Jan. 1, 1918.

Application filed September 9, 1915. Serial No. 49,653.

To all whom it may concern:

Be it known that I, JOHN W. STEPHENSON, a citizen of the United States, residing at Toledo, Lucas county, Ohio, have invented new and useful Improvements in Rail-Joints, of which the following is a specification, reference being had to the accompanying drawings, in which—

Figure 1 is a plan of my joint, showing one of the rails in section; Fig. 2 is an end elevation thereof; Fig. 3 is a section on lines III—III of Fig. 1, and Figs. 4 and 5 are details thereof.

My invention relates to rail joints and consists in a joint plate spanning the ends of the rails and containing wedging mechanism so arranged that the wedging action will be taken up principally between the heads and flanges of the rails thereby distributing the pressure so that the rail-engaging member is wedged firmly against the rail base, and the joint plate will be drawn up against the rail base. My invention also consists in the construction and arrangement of parts which I shall hereinafter describe and claim.

Referring to the drawings, the numeral 2 designates end portions of adjacent rails, 3 the usual cross ties and 4 the base or joint plate, preferably located between the ties. The joint plate 4 is preferably symmetrical in cross section, and has upturned and inwardly inclined sides 5, 5'. The rail engaging member 6, which extends across the joint between the ends of the adjacent rails, is adapted to have a supporting engagement with the heads 7 of the rails, and its lower portion 8 bears on its rear side against the undercut inner face of the side 5 of the plate and on its under side against the upper faces 9 of the flanges.

On the side of the rails opposite the member 6 is another rail-engaging member 10, which likewise extends across the joint between the ends of the rails and engages them between their flanges 9' and their heads 7. The rail-engaging member 10 is provided on its rear face with a laterally extending rib 11 on its lower or rail-base engaging portion, which has a flat horizontal upper surface 11^a, and above which its rear faces 12 incline outwardly from the ends toward the center of the member. Between the inclined faces 12 of the member 10 and the upturned side 5' of the joint plate 4, the wedges 13 are intended to be driven,

which bear laterally on one side against the rear faces 12 of the rail-engaging member, and on the other side against the undercut face of the side 5' and also bear downwardly upon the upper face 11^a of the rib 11. The 60 wedges 13 are held in position by bendable keys 14 seating in guideways 15, having heads 16 which bear against the ends of the wedges and hold them in locked position.

As the wedges 13 are driven in, their inner faces wedge against the horizontally-inclined surfaces 12 of the member 10, which forces the wedges outwardly against the vertically-inclined inner face of the side 5' of the joint plate, and this vertically-inclined 70 face in turn forces the wedge downwardly upon the rib 11 of the rail-engaging member 10, and thus transmits a large proportion of the wedging action through the rail-engaging member 10 to the rail base. As the 75 wedges 13 travel inwardly along the faces 12 of the member 10 there is no tendency of the wedges to slip off sidewise down the incline of the undercut inner face of the side 5', because the level surface 11^a prevents 80 such movement, and hence the wedging pressures force the member 10 down on the base flange of the rail and the joint plate is at the same time drawn up against the rail base. It will thus be seen that practically 85 the entire wedging action is exerted upon the rail-engaging member 10, a part of the pressure holding that member tight laterally against the rails, and part of the pressure forcing the member 10 downwardly upon 90 the base flanges of the rails thereby holding the rails firmly against the base plate and against movement relative to each other without undue pressure on the sides 5 and 95 5' of the joint plate.

To prevent longitudinal movement of the joint as a whole, relative to the rails, bosses 17 may be provided on the rail-engaging member 10, which enter the usual bolt holes nearest the ends of the rails and extend 100 through the rails a sufficient distance to enter the sockets 18 in the rail-engaging member 6. To hold the joint central with respect to the rail-ends, and particularly to keep the two rail ends in position in case 105 of breakage, I prefer to employ bolts 19 which are inserted through bolt holes 20 in the rail-engaging member 6, and through the usual bolt holes in the rails farthest from the rail ends. To provide a bearing against 110

the ends of the rail-engaging member 10, washers or retainers 21, mounted on the bolts 19 are employed. The bolts 19 are also useful in event of the breakage of either the member 6 or the member 10, as they will hold the parts in place and prevent the rails from working apart, since the wedging engagement will be maintained, inasmuch as the members 6 and 10 are held against longitudinal movement. I have also shown the member 6 equipped with outwardly extending lips 22 which take about the ends of the side 5 and hold the base 4 in alinement with the member 6 and therefore with the rails and member 10.

The terms and expressions which I have employed are used as terms of description and not of limitation, and I have no intention, in the use of such terms and expressions, of excluding any mechanical equivalents for the features shown and described, but recognize that various structural modifications are possible within the scope of the invention claimed.

25. What I claim is:

1. A rail joint comprising a base member having upturned sides, a rail gripping member extending across the joint between the ends of the rails, said rail gripping member having a horizontal non-wedging surface and an inclined wedging surface, a wedge adapted to be driven between said rail gripping member and an upturned side of said base member and to be supported upon said horizontal non-wedging surface, whereby its entire wedging pressure will be directed against said inclined wedging surface to force the rail gripping member laterally into engagement with the rail.
2. A rail joint comprising a base member having upturned sides, a rail gripping member extending across the joint between the ends of the rails, said rail gripping

member having a wedging surface inclined vertically and longitudinally of the rail, and also having a horizontal non-wedging surface, said upturned sides of the base member presenting inclined undercut surfaces of lesser inclination from the horizontal than the correspondingly-inclined surface of said gripping member, and a wedge adapted to be driven between said inclined surfaces and to be forced by said surfaces downward upon said horizontal non-wedging surface of the rail gripping member.

3. A rail joint comprising a base member having upturned sides, rail-gripping members extending across the joint between the ends of the rails, wedging means adapted to be driven between one of the rail gripping members and an upturned side of the base member adapted to wedge the last named rail-gripping member against the heads and bases of the rails, and means, supplemental to the wedging means and separate from the rail-gripping members, for holding the rail-gripping members in relative position.

4. A rail joint comprising a base member having upturned sides, rail-gripping members extending across the joint between the ends of the rails, wedging means adapted to be driven between one of the rail-gripping members and an upturned side of the base member, adapted to wedge the rail-gripping member against the heads and bases of the rails, and bolts seated in apertures in one of the rail-engaging members, adapted to hold the rail-gripping parts in alinement, supplemental of the wedging means.

JOHN W. STEPHENSON.
